UNITED STATES PATENT OFFICE.

MITCHELE DE LA FONTAINE, OF NEW YORK, N. Y.

COMBINATION PHONOGRAPH AND PICTURE-REPRODUCER.

1,303,217.

Specification of Letters Patent.

Patented May 6, 1919.

Application filed July 9, 1917. Serial No. 179,376.

To all whom it may concern:

Be it known that MITCHELE DE LA FONTAINE, a citizen of the Republic of Mexico, and resident of New York, in the county of 5 New York and State of New York, have invented certain new and useful Improvements in Combination Phonographs and Picture-Reproducers, of which the following is a specification.

10 This invention relates to a device essentially adapted for attachment to a phonograph and it is designed to project a picture on a screen depicting a sequence of events.

The object of the invention is to provide 15 the sound reproducing machine with a disk having pictures photographed in spiral formation thereon, and means connected to the phonograph actuating devices for moving the lens in unison with the pictures 20 trayed on the screen.

The invention comprehends devices connected to the picture disk operating means for controlling the movement of the lens so that it will be timed to move in unison relative to the progression of the pictures in 25 their eccentric revolution about the axis of the disk. In other words it is the fundamental object of these devices to actuate the lens step by step to register with each picture 30 from the outer radius of the spiral to its termination near the axis of the disk.

The other objects of the invention will be more fully described in the following specification and claims and illustrated in the accompanying drawings, forming part of this 35 specification, in which:—

Figure 1 represents a side elevation of a phonograph embodying this invention.

Fig. 2 represents a front view thereof with 40 the screen removed.

Fig. 3 represents a plan view thereof with parts broken away.

Fig. 4 represents an enlarged horizontal view of the lens feeding arms, partly in 45 section.

Figs. 5 and 6 represent cross-sections taken on line 5-5 of Fig. 3 and shows the teeth of the feeding arms engaging the master disk in different positions.

50 The invention, as shown in the drawings, is applied to a phonograph which may be of any kind or manufacture, of the disk-record type. The letter *a* designates the casing of the phonograph and has embodied therein an 55 amplifying horn *b*. The sound record carry-

ing plate *c* is rotated by the central shaft *d* actuated by the driving mechanism or motor, not shown. The sound record *e* is carried by the plate *c*. The reproducing arm *f* with its sound box *g* is mounted on the 60 phonograph in the usual way.

To the casing *a* of the phonograph are secured uprights *h* which are connected to a horizontal frame *i* which serves as support for the picture exhibiting and master disks 65 with its connections. A brace *j* is fastened to the lower portion of the uprights *h* and serves as support for the screen *k*, onto which the pictures are projected. This screen is made of translucent material, such as muslin or the like. It is to be understood that 70 the position of the screen may be varied according to the focal length of the lens.

To the end of the shaft *d* is fastened or held in frictional engagement therewith a 75 spindle *l*, mounted to turn in a bearing *m* fastened to frame *i*. Above the bearing *m* is secured an intermittent gear *n* with one tooth, meshing into a mutilated crown gear *o* mounted to revolve in a bearing *q* fastened 80 to the frame *i*. At the back of the gear *o* is a bevel gear *u* meshing into a small bevel gear *v* fastened to a cam shaft *w* supported at each end in bearings 12 and 13 fastened to frame *i*. A transmission shaft *p* is mounted 85 to revolve in suitable bearings 10 and 11 secured to frame *i*. At the front end of said shaft is fastened by a thumb-nut or other suitable fastening device, so as to admit adjustment, a disk *r*. This disk is made of 90 glass or other suitable material and has upon the face thereof small positive photographically produced pictures, arranged in a helical or spiral path.

At the rear end of the transmission shaft 95 *p* and in close proximity to the rear portion of frame *i* is fastened a master disk *t*, which is preferably made of tempered steel, having holes *t'* arranged in a helical or spiral path. The center of the holes as well as the spiral 100 path are identical with the center of the pictures on the picture disk *r*, the object of this to be explained later.

The shaft *w* has a cam member *w'* attached thereto for the co-operation of a lug 105 20 attached to a rocking arm 16 and at the end thereof adjacent to bearing 12 is attached a collar 22. Its purpose will be explained later.

To the bearing 13 and slightly below the 110

center of shaft w is fastened a short horizontal rod 14. Upon this rod the rocking arms oscillate and slide. The rocking arms at one end are made integral with a journal 5 which is mounted in a bearing 17, formed in one end of a carriage 15, and is held in position by a collar 18. The rocking arms are adapted to straddle the master disk t . To the inside of the outer ends of the arms are 10 fastened tapered pins 19, see Fig. 4, which are radially in alinement with the focal center of the lens. The pins are positioned one above the other at opposite arms vertically, see Figs. 5 and 6. To the arm 16 directly 15 opposite pin 19 is an outward projecting lug 20.

It will now be seen, that the spindle l revolves with a uniform motion received from the motor. The interrupted gears n 20 and o impacts an intermittent motion to the camshaft w by reason of gears u and v . The cam w' at each revolution comes in contact with the lug 20, will cause the arms 16 and 16' to rock to one side, and as soon as the 25 cam w' is out of engagement with the lug, the spring 21 which is fastened to the under side of the carriage 15, will return the arms to their first position.

By referring to Fig. 5, it will be seen that 30 the hole marked t' in the disk t is in alinement with the camshaft w . It is, therefore, also in alinement with the focal axis of the lens. One of the pins 19 has passed into the hole above, and is holding the disk firmly 35 while the picture is thrown on the screen. When the cam w' comes in contact with the lug 20, the pin above referred to is disengaged from said hole in the disk, and the lower pin will enter a hole two spaces below, 40 thereby moving the disk one half the distance between the holes, see Fig. 6. As soon as the cam has disengaged the lug 20, the spring 21 returns the arms to a position shown in Fig. 5, and the disk t will have 45 moved the distance of one hole. It will also be seen, that the pins 19 are bent and form an arc described from the center of rod 14. The outer end of said pins are tapered downward, and as they come in contact with the 50 lower portion of a hole and are forced into same, will cause the disk to move in the direction of the arrow.

Therefore, as the camshaft is rotated, the 55 rocking arms will cause the pins to enter the holes in the disk and impart to same an intermittent motion. The pins will engage the holes successively and engage same in the spiral path, thereby turning the two disks in unison and at the same time the 60 rocking arms are also moved toward the axis of the disks.

At the end of the spiral or when the last 65 hole has been reached the lug 20 will have passed the cam w' and will be in contact with the collar 22 on camshaft w holding the

arms in a neutral position and preventing any further movement of the disks. When the phonograph has been stopped, the carriage 15 can be moved back to the starting point and the pictures repeated or a new 70 picture disk attached.

The carriage 15 is supported by a roller 23, pivoted in a yoke formed in the frame, which rolls on the top of the frame i forming a track therefor. The frame has at its 75 forward end a bifurcated arm 24, bent at a right angle therewith into which the picture disk revolves. To the outer part of said arm is attached a projecting lens 25 and to the opposite part an electric lamp 26 with 80 a suitable reflector. The lamp may be supplied with electric energy from any suitable source, such as a battery.

From the foregoing description, it is obvious that the motion transmitted to the 85 rocking arms, will cause the disks r and t to move in unison with an irregular step by step motion. When a record is to be exhibited, the carriage 15 is placed to the extreme right with one pin of the rocking arm 90 95 engaging a hole in the master disk. As the phonograph is started, the pins in the rocking arms will alternatively engage the holes in the master disk, causing the same to rotate. The pins will engage the holes in the spiral path alternatively and cause the carriage 15 with its lens and lamp to move in a rectilinear path toward the center of its axis. By reason of the peculiar formation of the cam w' it will be seen that it takes a complete 100 revolution of the camshaft to effect a change from one picture to another. The cam will bring the picture into and allow the same to remain in the illuminated field for a predetermined time, the interval of the exposure 105 110 being greater than the time required to effect a change.

Owing to the great number of pictures on a disk, it may be necessary to repeat the music several times over, while the pictures 110 are exhibited. This may be accomplished by any well known repeater now in the market.

It is also evident that while the apparatus is in operation, the lens travels in a rectilinear path toward the center of the disk. The focal center of the lens also changes, and consequently at the beginning of an exhibition the pictures will first be projected on the screen close to one edge, and gradually move 115 toward the opposite side. It will be understood, that the apparatus must be operated in a darkened room. The pictures are projected onto the translucent screen from a positive with opaque background and must 120 be viewed by the audience at the other side of the screen. In other words, the lens moves in a radial line always at the same distance relative to the picture disk beginning 125 at its greatest radius or outer convolution of 130

pictures and terminating at the convolution adjacent to the axis of the disk.

I claim:—

1. In a moving picture machine, the combination with a disk having pictures in spiral formation thereon, means for intermittently rotating the disk; of a master disk connected to the picture disk, means for moving the master disk in unison with the picture disk, and a lens actuated by the master disk.

2. In a moving picture machine, the combination with a disk having pictures in spiral formation thereon, means for intermittently rotating the disk; of a master disk connected to the picture disk, means for rotating the master disk in unison with the picture disk, and a lens actuated by the master disk in a rectilinear line with the radius of the picture disk.

3. In a moving picture machine, the combination with a disk having pictures in spiral formation thereon, means for intermittently rotating the disk; of a master disk

having perforations in spiral formation, 25 means coacting with the perforations connected to the driving devices for rotating the disk in unison with the picture disk, and a lens actuated by the master disk in rectilinear 30 ear line with the radius of the picture disk.

4. In a moving picture machine, the combination with a disk having pictures in spiral formation thereon, means for intermittently rotating the disk; of a master disk having perforations in spiral formation, 35 means coacting with the perforations connected to the driving devices for alternatively interrupting and oscillating the disk in unison with the picture disk, and a lens actuated by the master disk in a rectilinear 40 line with the radius of the picture disk.

Signed at New York in the county of New York and State of New York this 9th day of June A. D. 1917.

MITCHELE DE LA FONTAINE.
